METALLIC WOOL PAD AND BINDING
THEREFOR

Robert F. Seelenbinder, Springfield, Ohio, assignor to International Steel Wool Corporation, Springfield, Ohio, a corporation of Ohio

Application March 23, 1935, Serial No. 12,630

15 Claims. (Cl. 140—71)

This invention relates to metallic wool manufacturers and more particularly to a metallic wool fabric suitable for binding pressing pads and for sundry other purposes and the method of making the same.

Metallic wool has long been used as a padding material for pressing machines for which it is well adapted, because of its elasticity, non-absorbent qualities and resistance to deterioration under influence of heat and moisture. It has been customary to provide a marginal binding of asbestos cloth or other non-metallic fabric upon such pressing pads. It is, however, desirable to have all parts of the pad of uniform character and material, and hence the present form of metallic wool fabric affords a desirable substitute for such non-metallic binding material. It is to be understood, however, that the metallic wool fabric forming the subject matter hereof is not limited to such application, but is applicable to many other purposes, in arts far removed from pressing pads. Its association with pressing pads in the present disclosure is for illustrative purposes and with no intent to unduly limit the invention.

The object of the invention is to provide metallic wool fabric in strip, sheet or ribbon form of any desired width which will be strong, durable, flexible, efficient in use, substantially unaffected by heat and moisture and capable of being rapidly and economically manufactured.

With the above primary and other incidental objects in view, as will more fully appear in the specification, the invention consists of the features of construction, the parts and combinations thereof, and the mode of operation, or their equivalents, as hereinafter described and set forth in the claims.

In the drawing wherein is shown the preferred but obviously not necessarily the only form of embodiment of the invention, Fig. 1 is a perspective view of a conventional form of metallic wool pad having thereon a marginal binding of metallic wool fabric forming the subject matter hereof. Fig. 2 is a perspective view of a portion of a fabricated metallic wool strip or ribbon. Fig. 3 is a perspective view illustrating a method of manufacture of such fabric.

Like parts are indicated by similar characters of reference throughout the several views.

Referring to the drawing, 1 is a metallic wool pressing pad such as is used upon steam garment pressing machines. The pad 1 may be of tangled or felted metallic wool, or it may consist of metallic wool fabric comprising rovings of metallic

wool systematically arranged in substantially parallel relation and united by transverse tie wires which may be either knitted or woven or otherwise interlaced about the metallic wool strands or rovings. Such fabricated metallic wool padding material is available upon the market and its particular construction and character forms no part per se of the present invention.

Disposed about the margin of the pad 1, as illustrated in Fig. 1, is a binding strip or ribbon 2, also of metallic wool material, which in combination with a metallic wool pad or apart therefrom, and its method of manufacture, form the subject matter hereof. The strip or ribbon 2 used to bind the pad 1 comprises longitudinal strands 3 of substantially parallel metallic wool fibers arranged in a relatively flat series or approximately common plane. Disposed transversely of the longitudinal material 3 are transverse strands 4 of metallic wool material, also arranged in substantially parallel relation. However, in lieu of being interwoven or interlaced with the longitudinal strands, the transverse material is wrapped around the assembly of longitudinal strands, thereby affording a continuation of transversely disposed transverse material on opposite sides of the longitudinal material throughout the extent of the fabric. While there is no directional interlacing or weaving of the respective materials, nevertheless the fibers of the longitudinal and transverse strands will intertwine or interlock with each other sufficiently to retain the assembly of transversely disposed strands in a unitary strip or ribbon form.

The longitudinal and transverse strands may be of the same material and of the same or different degree of fineness, or the longitudinal and the transverse strands may comprise fibers or shavings of different metals and whether the same or different metals, may be of different grades or character.

In the manufacture of the metallic wool fabric it has been found practical and economical to collect together loosely a roving of fibers as they come from a metallic wool making machine, to form the longitudinal strands 3, and to loosely wind progressively thereabout a second roving of fibers as they also come from the wool making machine to form the transverse strands 4. This assembly of longitudinal strands with the transverse strands wrapped helically thereabout is then passed between pressure rollers 5 by which the materials are compressed into relatively thin flat sheet or ribbon 2. The resulting strip of sheet material is of laminated construction con-

sisting of an intermediate stratum of substantially longitudinally disposed fibers and exterior strata of transversely disposed fibers on opposite sides of the longitudinal fibers. Such ribbon may 5 be made of different widths or of different thickness by correspondingly varying the quantity of material and the degree of tightness with which the transverse material is wrapped around the longitudinal strands. The pressing and manipulation of the material not only reduces it to 10 a thin flat sheet form but also effects an interlocking or felting of the transversely disposed fibers with each other.

While as illustrated the resulting fabric is useful and desirable for binding pressing pads of metallic wool and the like, it is also applicable to 15 a wide variety of other purposes, such as filter sheets, cover sheets and the fabric when cut into sections and superposed one upon another may 20 be formed into pressing pads such as shown at 1. Such laminated construction facilitates the formation of contoured form retaining pads.

From the above description it will be apparent 25 that there is thus provided a device of the character described possessing the particular features of advantage before enumerated as desirable, but which obviously is susceptible of modification in its form, proportions, detail construction and arrangement of parts without departing from the 30 principle involved or sacrificing any of its advantages.

While in order to comply with the statute, the invention has been described in language more or less specific as to structural features, it is to 35 be understood that the invention is not limited to the specific features shown, but that the means and construction herein disclosed comprise the preferred form of several modes of putting the invention into effect, and the invention is therefore claimed in any of its forms or modifications 40 within the legitimate and valid scope of the appended claims.

Having thus described my invention, I claim:

1. A pressing pad and a marginal binding strip 45 therefor of metallic wool material comprising a separately formed flat binding strip of transversely arranged interfelted strands of metallic wool material for enclosing the margins of the pad when secured thereto.

2. A metallic wool pressing pad and a marginal binding strip therefor of metallic wool material comprising superposed interfelted strata of metallic fibers formed into a continuous strip of metallic wool fabric secured about the margins of 50 the pad and confined thereto.

3. A metallic wool pressing pad and a marginal binding strip therefor formed of transversely disposed interfelted strands of metallic wool material secured about the margins of the pad and 55 confined thereto.

4. As an article of manufacture, a sheet fabric comprising a single flat layer of longitudinal and double layer of transverse strands of metallic wool fibers, the transverse fibers being helically disposed in contacting convolutions extending exteriorly about opposite sides of the longitudinal 60 strands.

5. As an article of manufacture, a thin flat 70 flexible metallic wool fabric comprising a single layer of longitudinally disposed fibers of indeterminate length and transverse rovings of metallic fibers wrapped transversely and progressively about the longitudinal fibers in continuous contacting convolutions forming parallel external

layers extending continuously on opposite sides of the layer of longitudinal fibers.

6. As an article of manufacture, a thin flat ribbon-like strip of flexible metallic wool fabric comprising a single layer of longitudinally disposed metallic fibers of indeterminate length and transversely disposed rovings of metallic wool fibers contacting with each other and interfelted with the longitudinal fibers, the assembly being compressed into sheet formation. 5

7. The herein described method of manufacturing metallic wool fabric consisting in progressively winding successive contacting turns of a roving of metallic wool material transversely about a longitudinal roving of metallic wool material and subsequently compressing the assembly 15 into flat sheet formation wherein the transverse and longitudinal strands of material comprising the respective rovings are interfelted with each other. 20

8. As an article of manufacture, a marginal binding for a preformed metallic wool pressing pad comprising a separately formed metallic wool binding strip of interfelted longitudinal and transverse metallic strands confined to and enclosing 25 the margins of the pad.

9. As an article of manufacture, a marginal binding for a metallic wool pressing pad comprising longitudinal metallic wool strands of indeterminate length and transversely disposed metallic wool rovings progressively wound about the longitudinal strands with their successive convolutions in contacting relation and interfelted therewith into a continuous unitary strip disposed about and united with the margins of the 30 pad. 35

10. A metallic wool fabric comprising a thin flat flexible ribbon including longitudinally disposed strands of metallic wool of indeterminate length and transverse strands of metallic wool disposed in continuous progressing contacting convolutions about said longitudinal strands and combined with the longitudinal strands into a continuous unitary strip. 40

11. A metallic wool fabric comprising a thin flat flexible sheet material including longitudinally disposed strands of metallic wool of indeterminate length and transverse roving of metallic wool helically wound about said longitudinal strands in successively contacting convolutions extending about opposite sides of the longitudinal 45 strands. 50

12. A metallic wool fabric comprising a thin flat flexible sheet material including longitudinally disposed strands of metallic wool of indeterminate length and a transverse roving of metallic wool strands helically wound about the longitudinal strands with the successive convolutions thereof in contacting relation and interfelted with the longitudinal strands thereby 55 forming superposed strata with the longitudinal strands extending intermediate two external strata of transverse strands. 60

13. A metallic wool fabric comprising a thin flat flexible sheet material including longitudinally disposed strands of metallic wool of indeterminate length and a helical winding of transverse strands thereabout the said transverse strands being continuous about the longitudinal margins and across both sides of the assembly 65 of longitudinal strands and interfelted therewith. 70

14. The herein described method of producing metallic wool fabric consisting in winding progressive contacting convolutions of a roving of metallic wool strands helically about a second 75

roving of longitudinally disposed strands of indeterminate length and compressing the assembly into a relatively thin flat flexible sheet formation.

15. The method of producing metallic wool fabric consisting in disposing a series of relatively small diameter rovings transversely of a

relatively large diameter roving of longitudinally disposed strands and pressing the assembly into flat flexible sheet formation with the roving of longitudinally disposed strands extending substantially throughout the sheet.

ROBERT F. SEELENBINDER.

CERTIFICATE OF CORRECTION.

Patent No. 2,192,590.

March 5, 1940.

ROBERT F. SEELENBINDER.

It is hereby certified that error appears in the printed specification of the above numbered patent requiring correction as follows: Page 2, first column, line 57, claim 3, strike out the word "strip"; and that the said Letters Patent should be read with this correction therein that the same may conform to the record of the case in the Patent Office.

Signed and sealed this 30th day of April, A. D. 1940.

Henry Van Arsdale,
Acting Commissioner of Patents.
